UNITED STATES PATENT OFFICE.

WILLIAM CLAYTON CORYELL, OF YOUNGSTOWN, OHIO, ASSIGNOR TO THE GENERAL FIREPROOFING COMPANY, OF YOUNGSTOWN, OHIO, A CORPORATION OF OHIO.

CLIP FOR CORNER BEADS.

Application filed May 10, 1922. Serial No. 559,887.

To all whom it may concern:

Be it known that I, WILLIAM CLAYTON CORYELL, citizen of the United States, residing at Youngstown, in the county of Mahoning and State of Ohio, have invented certain new and useful Improvement in Clips for Corner Beads, of which the following is a specification.

This invention relates to a novel clip device for supporting and holding corner beads that are used in building construction to reinforce the corners of the plastered walls of rooms and the like.

It is the well known and usual practice in finishing the corners of walls to utilize a clip for connecting the corner bead to the nailing ground or other point of support, the said clip constituting a conveniently attached extension that projects into the zone of the support thereby to permit of the clip being easily secured into position to carry the bead. In order to facilitate erection or installation it is desirable that the clip have a quick coupling engagement with the bead and then be positioned so that it may project substantially at right angles to the bead and support or carrying the same in the desired position.

Accordingly, the present invention has primarily in view a novel clip that may be made by stamping from sheet metal, and which has novel structural features and characteristics imparting strength and durability thereto, and at the same time permitting of its facile application to the bead.

A further object of the invention is to provide a clip that may be readily attached from the outside surface of the bead strip and which requires movement through a minimum arc in order to grip the opposite sides of the bead openings.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a detail view illustrating the application of the bead and the clip to the

corner of a room wherein wooden framing is used.

Figure 2 is a horizontal sectional view illustrating the application of the invention to a hollow tile or other fire proof wall.

Figure 3 is a perspective view of the improved clip.

Figure 4 is a vertical sectional view taken on the line 4—4 of Figure 3.

Similar reference characters designate corresponding parts throughout the several figures of the drawings.

In carrying the present invention into effect it is proposed to provide a clip body 1 having the reversely disposed lugs 2 and 3 both offset from the rear face of the clip and arranged in such a manner that the clip 70 may be conveniently attached by inserting one of the lugs in one of the openings A of the bead B while the other lug engages with the rear edge C of one of the flanges of the bead. That is to say, the arrangement and substantially triangular shape of the lugs 2 and 3 is such that the lower lug 2 may be readily inserted in one of the openings A by holding the clip at an angle of substantially 60° to the edge C at the face of the flange 80 and then placing the other lug 3 in position to engage behind the said edge C. Upon moving the clip to a position substantially at right angles to the edge C the web of the lug 3 which connects with the body 1 85 will engage with or bind against the edge C while the corresponding clip of the lug 2 will engage with the edge of the opening A. In that way the clip may be securely connected to the bead in such a manner that the latter will be adequately supported by the interlock thus established and maintained by the weight of the bead after the clip has been secured in place.

For the purpose of stiffening the body of the clip the central portion thereof is provided with a reinforcing rib 4 pressed outwardly from the face of the clip and terminating short of the edges thereby to leave a flat portion of the body at each end of the rib. This arrangement has been found effective in practical use and materially stiffens the clip against bending.

At each side of the rib 4 the body 1 is provided with openings 5 and 6, the former being adapted to receive nails or equivalent

fastenings for securing the clip to the wood framing or studding S as shown in Figure 1 while the elongated openings 6 serve as key openings for plaster or the like when the clip is to be supported by a plastic spot ground G used on tile or brick walls, as shown in Figure 2.

From the foregoing it will be apparent that the present invention aims to provide 10 a novel clip in which the bead engaging lugs are both offset from the same side of the plate, namely the rear side, thereby avoiding the necessity of placing the bead engaging end of the clip behind the flange 15 of the angular bead and enabling the connection to be readily made from the face of the flange without loss of time or extra labor. Also, by providing the stiffening rib 4 in the manner described the body is adequately reinforced, and also the body is provided with fastening receiving openings as 20 well as plastic key openings thereby adapting the clip to a wide range of uses.

Without further description it is thought 25 that the features and advantages of the present invention will be readily apparent to those skilled in the art and it will of course be understood that changes in the form, proportion and minor details of con-

struction may be resorted to without departing from the spirit of the invention or scope of the appended claims.

I claim:—

1. A clip for corner beads consisting of a body having bead engaging lugs, a reinforcing rib formed at the central portion of the clip, and key openings at opposite sides of the rib. 35

2. A corner bead clip consisting of a body having bead engaging lugs, a centrally arranged stiffening rib and also having elongated key openings and fastening receiving openings at opposite sides of the rib. 40

3. A clip for corner beads having reversely related bead gripping lugs struck out 45 from the rear face of the clip body, a stiffening rib formed longitudinally of the body and extending between the lugs but terminating short of the edges of the clip and said clip body and having fastening receiving openings at opposite sides of the rib. 50

In testimony whereof I hereunto affix my signature in the presence of two witnesses.

WILLIAM CLAYTON CORYELL.
